UNITED STATES PATENT OFFICE.

ABRAM W. WHEATON, OF NEWARK, NEW JERSEY.

FAUCET-NOZZLE.

1,318,120.

Specification of Letters Patent.

Patented Oct. 7, 1919.

Application filed March 8, 1919. Serial No. 281,461.

To all whom it may concern:

Be it known that I, ABRAM W. WHEATON, a citizen of the United States, residing at Newark, in the county of Essex and State 5 of New Jersey, have invented certain new and useful Improvements in Faucet-Nozzles; and I do hereby declare the following to be a full, clear, and exact description of the invention, such as will enable others 10 skilled in the art to which it appertains to make and use the same, reference being had to the accompanying drawings, and to characters of reference marked thereon, which form a part of this specification.

15 The present invention relates, generally, to improvements in faucets, particularly adapted for use upon oil and gasolene tank vehicles; and the invention relates, more particularly, to an improved self-closing 20 faucet and detachable operating handle for manipulating the same.

The invention has for its principal object to provide a novel construction of self-closing faucet adapted to be manipulated by a 25 novel detachable handle member constructed to coöperate with novel means connected with the faucet whereby the valve member may be held open until the handle-member is detached from said means. The invention 30 also provides a means for opening and holding open the faucet to its full extent or capacity, or to an intermediate partial extent, as may be desired.

The invention has for a further object to 35 provide a novel locking means for locking down the faucet valve upon its seat, so that the same is held in secured closed relation to the seat at all times until said locking means is released.

40 Other objects of the present invention, not at this time more particularly enumerated, will be clearly understood from the following detailed description of the same.

With the various objects of the invention 45 in view, the same consists, primarily, in the novel self-closing faucet and detachable operating handle-member therefor herein-after set forth; and the invention consists, furthermore, in the novel arrangements and 50 combinations of the various devices and parts, as well as in the details of the construction of the said parts, all of which will be more fully described in the following specification, and then finally embodied in 55 the claims which are appended to and which

form an essential part of the said specification.

The invention is clearly illustrated in the accompanying drawings, in which:

Figure 1 is a vertical longitudinal section 60 of the novel self-closing faucet showing the novel detachable handle member applied thereto in operative relation therewith.

Fig. 2 is a horizontal cross-section taken on line 2-2 in said Fig. 1. 65

Fig. 3 is a front end elevation of the upper portion of the novel faucet, the operating handle member being detached and removed therefrom.

Similar characters of reference are employed in all of the hereinabove described views to indicate corresponding parts.

Referring now to the said drawings, the reference character 1 indicates the faucet body providing in its lower end the interior 70 chamber or passage 2. Extending from the rear side of said faucet body is an internally screw-threaded extension 3 communicating with said chamber or passage 2, and adapted to receive the threaded end of the outlet 80 pipe of the tank vehicle (not shown), thus securing the faucet operatively thereto. Connected with the lower end of said faucet-body 1 is a downwardly extending nozzle-portion 4, which is provided within said faucet-body with a valve seat-portion 5 upon which seats itself, when in closed position, a vertically movable valve-member 6, upon which is secured a valve-washer 7 of suitable material. Connected with said valve-member 6 is an upwardly extending valve stem 8. The said faucet-body 1 is provided, above said chamber or passage 2, with a transverse horizontal partition or wall 9, having a centrally disposed opening forming a guideway 10 through which said valve stem 8 slidably extends. Said partition or wall 9 is provided, at the upper end of said guideway 10, with an annular depression 90 forming a packing seat 11, in which is arranged a suitable packing 12, adapted to embrace said valve stem 8, and thereby prevent leaking of any fluid upward through said guideway 10. A perforate keeper-plate 13, secured to the upper side of said 100 partition or wall 9, by screws 14, or other suitable fastening means, serves to retain said packing 12 against removal from said packing seat 11. Arranged about said valve stem 8, between said partition or wall 9 and 110

said valve member 6, is a spiral compression spring 15, the tension or pressure of which is exerted downwardly upon said valve member 6 to hold the same with its 5 washer 7 in closed or seated relation to the valve seat-portion 5.

Said faucet-body is provided, above said wall or partition 9 with an upwardly projecting tubular extension 16, having at its 10 upper extremity an externally threaded neck 17, adapted to receive a closing cap 18, which is internally threaded to screw upon said neck 17. Said valve stem 8 projects upwardly into the space 19 inclosed 15 by said extension 16 and the cap 18, and is provided adjacent to its upper end with a transverse slot or receiving opening 20. Extending upwardly from the upper extremity of said valve stem 8 is a reduced 20 extension 21 thereof, which is slidably disposed for vertical movement in a guideway 21' provided in said closing cap 18. Formed in the front side of said tubular extension 16 is an opening or hatchway 22, providing 25 access to the valve stem 8 for the detachable operating handle member to be presently described. The lower end of said opening or hatchway 22 is formed to provide a fulcrum member 23, the purpose of 30 which will presently appear. Pivoted to the exterior surface of said extension 16 is a closure-member 24 which may be swung down across the opening or hatchway 22 to close same against the entrance of dirt, dust 35 or other objectionable foreign substances therethrough and into the valve stem inclosing space 19. A stop projection 25 determines the closed position of said closure-member 24, as may be seen from an inspection 40 of Fig. 3 of the drawings.

The closing cap 18 is provided with a transverse vertical slot 26, through which extends a fulcrum pin 27. Pivoted upon said fulcrum pin is a lock-cam 28 provided with an outwardly extending lever-arm or finger-piece 29 for manipulating the same. When said lever-arm or finger-piece is turned downward the lock-cam 28 is swung inwardly and thereby engages 45 the end of the reduced extension 21 of the valve-stem 8, exerting a downward pressure thereon so that the valve-member 6 with its washer 7 is locked firmly in seated relation to the valve seat-portion 5. Since the downward movement of the lever-arm or finger-piece 29 carries the free end of the same in contact with the body of the closing cap 18, the lock cam is stopped against further upward movement, when the same is once engaged with the extension 21, and consequently any tendency to upward movement of the valve member 6 and its washer 7 away from the valve seat-portion 6 is securely 55 blocked by the pressure of the lock-cam 28 against the extension of the valve-stem.

When it is desired to operate the valve, the finger-piece or lever-arm 29 is raised or swung upward, this movement swinging the lock-cam 28 outwardly and away from the end of the extension 21 of the valve-stem 8, 70 and clear of its path of movement in the guideway 21' of the closing cap 18, so that upward movement of the valve-stem, and consequently lifting movement of the valve-member 6 and its washer 7 is in no way interfered with, as is shown in Fig. 1 by the dotted line position of the lock-cam 28 and its finger-piece 29.

To operate or open the faucet it is necessary to impart an upward movement to 80 the valve stem 8 to lift the valve member 6 and its washer 7 from the valve seat-portion 5, against the tension of the spring 15, thereby allowing the fluid entering the faucet to pass outward through the nozzle-portion 4. To so operate the parts I provide a novel construction of detachable and independent handle-member, which comprises a lever-member 30 having a hand-grip portion 31 connected therewith. Said lever-member 30 is provided, preferably with a fulcrum-notch 32 on its under side. Pivotally connected with said lever-member 30 is a downwardly and forwardly inclined latch-arm 33, having at its upper end a perforate 90 ear 34 which is disposed in a receiving-opening 35 provided in the body of said lever-member therefor, a fulcrum pin 36 being passed transversely through the body of said lever-member and said perforate ear 34 to 100 pivotally connect said latch-arm 33 in operative relation to said lever-member. Connected with said latch-arm 33, so as to extend outwardly therefrom in downward inclination beneath the hand-grip portion 31 105 of said lever-member 30, is a trigger-arm 37. Connected with the under side of said hand-grip portion 31 of said lever-member 30 is a leaf spring 38, the free end of which bears downwardly upon said trigger-arm 37 110 to swing the same downward, and thereby swing forward the lower end of said latch-arm 33. The lower end of said latch-arm 33 is provided with a forwardly projecting latch-nose 39, which may be caused to engage one of a plurality of catch-nosings 40 115 rigidly projecting outwardly from the outer surface of the faucet body 1.

In operation, the closure-member 24 is swung upwardly to uncover the opening or 120 hatch-way 22, and the free end of the lever-member 30 is inserted therethrough until engaged in the transverse slot or receiving opening 20 of the valve-stem 8. In order to prevent the said transverse slot or receiving opening 20 from being displaced from properly aligned relation to said opening or hatchway 22 by the twisting or turning of the valve-stem 8, the latter is provided in its body with a vertical slot 41 through 125 130

which is passed a retaining pin 42, the latter being supported in the body 1 of said faucet. As will be apparent said valve-stem may move vertically relative to said pin 42 within limits determined by the length of the slot 41, but is prevented by the pin 42 from turning axially. The free end of said lever-member 30 being engaged in said receiving opening 20 of the valve stem 8, the lever-member 30 is then lowered so that its fulcrum notch 32 is engaged upon the fulcrum member 23 at the lower end of said opening or hatchway 22. The trigger-arm 37 is now swung upwardly toward the hand-grip portion 31, against the tension of the leaf-spring 38, thereby swinging backward said latch-arm 33, and then a downward swinging movement is imparted to said hand-grip portion 31, which swings upward said free end of the lever-member 30, and consequently lifts upward said valve-stem 8, thereby raising said valve-member 6 and its washer 7 away from the valve seat-portion 5, against the tension of the spring 15. In order to hold the valve-member and its washer in partly opened relation to the valve seat-portion 5, the latch-nose 39 of the latch-arm 33 is positioned opposite the uppermost catch-nosing 40, and then by releasing the trigger-arm 37, the latch-arm is swung forwardly to engage said latch-nose 39 with said uppermost catch-nosing 40, thereby holding or retaining said hand-grip portion 31 in its downwardly turned position, and said free end of said lever-member 30 in its valve-stem raising position. If it is desired to open the valve-member to fully raised extent, to permit the faucet to vent fluid to its full capacity, then the operations above described are carried out, except that the latch-nose 39 of the latch-arm is engaged with the lowermost catch-nosing 40, which holds the lever-member 30 to a complete up-swing position, with a consequent increased amount of lift being imparted to the valve-stem 8, whereby the valve-member 6 and its washer 7 is completely raised to full extent away from the valve seat-portion 5.

Of course, it will be apparent that by disengaging the latch-arm 33 from either catch-nosing 40, the swing of the lever-member 30 may be reversed, so that said valve-stem 8 is permitted to move downward, and the valve-member 6 and its washer 7 is permitted to again engage the valve seat-portion 5 in closing relation thereto. The handle-member may then be removed, and the valve locked down by the lock-cam 28, and the opening or hatchway 22 closed by the closure-member 24, so that all parts of the faucet resume normal initial positions.

The nozzle-portion 4 is preferably exteriorly screw-threaded, as indicated at 43, for the reception of the internally threaded cap 44, which is provided at intervals, upon

its periphery, with ears 45, having apertures 46 therein.

Extending from the front of said faucet-body 1 and integral therewith is a hook 47, upon which a bucket or can may be hung while the same is being filled. Pivoted to this hook, near the faucet body is a hasp 48, which is adapted to embrace one or the other of said ears 45, and extends sufficiently over said ear to expose its aperture 46 for the reception of a lock (not shown), whereby said cap is locked upon said nozzle-portion against surreptitious removal.

I am aware that some changes may be made in the several arrangements and combinations of the various devices and parts, as well as in the details of the construction of the same, without departing from the scope of the present invention as set forth in the foregoing specification, and as defined in the appended claims. Hence, I do not limit my invention to the exact arrangements and combinations of the several devices and parts as described in the foregoing specification, nor do I confine myself to the exact details of the construction of the said parts as illustrated in the accompanying drawings.

I claim:

1. The combination with a faucet body of a self-closing valve having an upwardly extending stem, a transverse partition within said body to divide the interior of the latter to provide a fluid-free chamber in its upper end, said partition having a centrally disposed guideway through which said stem extends to project the upper end of the latter into said fluid-free chamber, packing supporting and retaining means connected with said partition, a packing embracing said stem, the upper end of said stem having a transverse receiving slot therein, said faucet body having an opening in its wall aligned opposite said receiving slot of said stem giving access to said fluid-free chamber, a detachable lever means adapted to be passed through said opening and into said receiving slot of said stem for lifting said valve, said lever means when operatively arranged being fulcrumed on the bottom of said opening co-operating means connected respectively with the exterior of said faucet body and said lever means adapted when mutually engaged to hold said lever means in valve lifting position, and a pivoted lock cam device connected with the upper end of said faucet body to be movable into engagement with the upper end of said stem to lock said valve in closed position.

2. The combination with a faucet body of a self-closing valve having an upwardly extending stem, a transverse partition within said body to divide the interior of the latter to provide a fluid-free chamber in its upper end, a cap for closing the upper end of said

fluid-free chamber, said partition having a centrally disposed guideway through which said stem extends to project the upper end of the latter into said fluid-free chamber,
5 said partition having an annular packing socket surrounding said stem, a packing seated in said socket to surround said stem, means for retaining said packing in said socket, the upper end of said stem having
10 a reduced extension, said cap having a guideway in which said reduced extension rides, means preventing axial rotation of said stem, said stem having a transverse receiving slot adjacent to its upper end, said
15 faucet body having an opening in its wall alined opposite said receiving slot of said stem giving access to said fluid-free chamber, and a detachable lever means adapted to be passed through said opening and into
20 said receiving slot of said stem for lifting said valve, said lever means when operatively arranged being fulcrumed on the bottom of said opening.
3. The combination with a faucet body of
25 a self-closing valve having an upwardly extending stem, a transverse partition within said body to divide the interior of the latter to provide a fluid-free chamber in its upper end, a cap for closing the upper end of said
30 fluid-free chamber, said partition having a centrally disposed guideway through which said stem extends to project the upper end of the latter into said fluid-free chamber, said partition having an annular packing
35 socket surrounding said stem, a packing seated in said socket to surround said stem, means for retaining said packing in said socket, the upper end of said stem having a reduced extension, said cap having a guideway
40 way in which said reduced extension rides, means preventing axial rotation of said stem, said stem having a transverse receiving slot adjacent to its upper end, said faucet body having an opening in its wall alined oppo-
45 site said receiving slot of said stem giving access to said fluid-free chamber, a detachable lever means adapted to be passed through said opening and into said receiving slot of said stem for lifting said valve,
50 said lever means when operatively arranged being fulcrumed on the bottom of said opening, a lock-cam pivoted to said cap, and a finger-piece connected with said lock-cam, said lock-cam being adapted to engage the
55 reduced extension of said stem to hold the same against upward movement thereby locking said valve in closed position.

4. The combination with a faucet body of
60 a self-closing valve having an upwardly ex-
tending stem, a transverse partition within
said body to divide the interior of the latter
to provide a fluid-free chamber in its upper
end, a cap for closing the upper end of
65 said fluid-free chamber, said partition hav-
ing a centrally disposed guideway through

which said stem extends to project the upper end of the latter into said fluid-free chamber, a packing supporting and retaining means connected with said partition, a packing embracing said stem, the upper end of said stem having a reduced extension, said cap having a guideway in which said reduced extension rides, means preventing axial rotation of said stem, said stem having a transverse receiving slot adjacent to its upper end, said faucet body having an opening in its wall alined opposite receiving slot of said stem giving access to said fluid-free chamber, a detachable lever means adapted to be passed through said opening and into said receiving slot of said stem for lifting said valve, said lever means when operatively arranged being fulcrumed on the bottom of said opening, a latch-member having a latch-nose pivoted to said lever means for downward and forward extension from the latter, a rearwardly extending trigger arm connected with said latch member, a leaf spring connected with said lever member to exert downward pressure on said trigger arm, and a fixed catch nosing projecting from the exterior surface of said faucet body with which said latch nose of said latch member may be engaged to hold said lever means in valve lifting position.

5. The combination with a faucet body of a self-closing valve having an upwardly extending stem, a transverse partition within said body to divide the interior of the latter to provide a fluid-free chamber in its upper end, a cap for closing the upper end of said fluid-free chamber, said partition having a centrally disposed guideway through which said stem extends to project the upper end of the latter into said fluid-free chamber, a packing supporting and retaining means connected with said partition, a packing embracing said stem, the upper end of said stem having a reduced extension, said cap having a guideway in which said reduced extension rides, means preventing axial rotation of said stem, said stem having a transverse receiving slot adjacent to its upper end, said faucet body having an opening in its wall alined opposite receiving slot of said stem giving access to said fluid-free chamber, a detachable lever means adapted to be passed through said opening and into said receiving slot of said stem for lifting said valve, said lever means when operatively arranged being fulcrumed on the bottom of said opening, a latch-member having a latch-nose pivoted to said lever means for downward and forward extension from the latter, a rearwardly extending trigger arm connected with said latch member, a leaf-spring connected with said lever member to exert downward pressure on said trigger arm, a fixed catch-nosing projecting from the ex-

terior surface of said faucet body with which said latch-nose of said latch-member may be engaged to hold said lever means in valve lifting position and a closure member for closing said opening when said lever means is withdrawn.

6. The combination with a faucet body of a self-closing valve having an upwardly extending stem, a transverse partition within 10 said body to divide the interior of the latter to provide a fluid-free chamber in its upper end, a cap for closing the upper end of said fluid-free chamber, said partition having a centrally disposed guideway 15 through which said stem extends to project the upper end of the latter into said fluid-free chamber, a packing supporting and retaining means connected with said partition, a packing embracing said stem, the 20 upper end of said stem having a reduced extension, said cap having a guideway in which said reduced extension rides, means preventing axial rotation of said stem, said stem having a transverse receiving slot adjacent to its upper end, said faucet body having an opening in its wall aligned opposite receiving slot of said stem giving access to said fluid-free chamber, a detachable lever means adapted to be passed through said 25 opening and into said receiving slot of said stem for lifting said valve, said lever means when operatively arranged being fulcrumed on the bottom of said opening, a latch-member having a latch-nose pivoted to said lever means for downward and forward extension from the latter, a rearwardly extending trigger arm connected with said 30

latch-member, a leaf-spring connected with said lever member to exert downward pressure on said trigger arm, a fixed catch nose 40 projecting from the exterior surface of said faucet body with which said latch-nose of said latch-member may be engaged to hold said lever means in valve lifting position and a closure member for closing said opening when said lever means is withdrawn, a lock cam pivoted to said cap, and a finger-piece connected with said lock cam, said lock cam when operatively positioned being adapted to engage the upper end of 45 said reduced extension of said stem to hold the same against upward movement thereby locking said valve in closed position.

7. The combination with a faucet body of a vertically movable valve having an upwardly extending stem, means for guiding said stem, a cap closing the upper end of said faucet body, said cap having a guideway in which the upper end of said stem rides, a lock cam pivoted to said cap, and a finger-piece connected with said lock cam for manipulating the same, said lock cam when operatively positioned being adapted to engage the upper end of said stem to hold the same against upward movement thereby locking said valve in closed position.

In testimony, that I claim the invention set forth above I have hereunto set my hand this 4th day of March, 1919.
